No. 713,231.

Patented Nov. 11, 1902.

C. B. MANSBACH.

COMBINED PUTTY KNIFE AND POT HANGER.

(Application filed Feb. 6, 1902.)

(No Model.)

UNITED STATES PATENT OFFICE.

CONRAD B. MANSBACH, OF CAMPOLLO, MASSACHUSETTS.

COMBINED PUTTY-KNIFE AND POT-HANGER.

SPECIFICATION forming part of Letters Patent No. 713,231, dated November 11, 1902.

Application filed February 6, 1902. Serial No. 92,787. (No model.)

To all whom it may concern:

Be it known that I, CONRAD B. MANSBACH, a citizen of the United States, and a resident of Campello, in the county of Plymouth and 5 State of Massachusetts, have invented certain new and useful Improvements in a Combined Putty-Knife and Pot-Hanger, of which the following is a specification.

This invention relates to a combined putty-knife and pot-hanger; and it is adapted for use as an ordinary putty-knife for puttying surfaces to be afterward painted, and it is also useful as a device for supporting a paint-pot or other device during the operation of 15 painting the roof or outside walls of a house, as will hereinafter be more fully shown and described, reference being had to the accompanying drawings, wherein—

Figure 1 is a side elevation of the improved 20 putty-knife and pot-hanger. Fig. 2 is a longitudinal section on the line 2 2 in Fig. 1, showing in dotted lines the pivoted portion of the handle swung outward when in use as a pot-hanger. Fig. 3 is a cross-section on the 25 line 3 3 in Fig. 1. Fig. 4 is a side elevation of the device shown in use as a pot-hanger, and Fig. 5 represents a detail perspective view of the hinged portion of the handle.

Similar letters refer to similar parts wherever they occur on the different parts of the drawings.

In the drawings, A represents the blade of a putty-knife as usual, to which is secured in a suitable manner the handle portion B, to 30 which is hinged at C the metal bar or plate D, preferably secured to the handle portion E, as shown.

To the lower portion of the handle portion E is secured an extension e, which may be secured 35 to the part E or made integral therewith, as may be most practical or convenient, without departing from the essence of my invention.

The metal plate D is provided at its upper 40 free end with pronged or pointed projections d d for a purpose as will hereinafter be more fully described.

In practice I prefer to secure to the blade A a projection A' for the purpose of serving as a frictional locking device relative to the 50 prongs d d when the handle is closed and the device used as a putty-knife.

In Fig. 4, F represents the outer wall of a wooden building, on which G G are the clapboards, as usual.

In using the device as a pot-hanger I place the upper end of the blade A between two of the clapboards G G and swing the handle portion E and its metal plate D to the position shown in dotted lines in Fig. 2 and full lines 60 in Fig. 4 and insert the prongs d d into one of the lower clapboards G, as shown in Fig. 4, after which I suspend the bail h of the pot H on the handle extension e, as represented in Fig. 4, in which position said pot H is properly held suspended during the operation of 65 painting the wall of the building.

I have shown the pot-hanging device as applied to a vertical wall; but it is equally useful on slanting roofs by inserting the end of 70 the blade A between the shingles of the roof in a similar manner to that shown in Fig. 4.

Having thus fully described the nature, construction, and operation of my invention, I wish to secure by Letters Patent and claim— 75

The herein-described combined putty-knife and pot-hanger, consisting of a putty-knife A, secured to a handle portion B, and pivotally connected to a metal plate D, having a pronged end d, and having secured to it a 80 handle portion E, provided with an extension e, projecting beyond the lower end of the handle portion B, and adapted to serve as a pot-hanger substantially as herein set forth and described.

In testimony whereof I have affixed my signature in presence of two witnesses.

CONRAD B. MANSBACH.

Witnesses:

ALBAN ANDRÉN,
AGNES J. CARLSON.
